UNITED STATES PATENT OFFICE.

GEORGE LANGFORD, OF JOLIET, ILLINOIS, ASSIGNOR TO MCKENNA PROCESS COMPANY OF ILLINOIS, OF JOLIET, ILLINOIS, A CORPORATION OF ILLINOIS.

SPLICE BAR.

Application filed April 25, 1927. Serial No. 186,217.

This invention relates to splice bars for use in rail joints, and more particularly to a splice bar of what is known as the balanced I-beam type, such bars having a comparatively thin base flange.

It has been the practice of railroad engineers for many years to construct rail joints with angle bars having base flange bearing portions extending outside of the rail flange and provided with slots or openings receiving spikes for anchoring the bars and, consequently, the rails to the ties so as to resist lateral and longitudinal movement. The advantages of thus anchoring the rails are obvious and well known. Great difficulty has been experienced, however, in anchoring the bars to the ties in the manner stated due to what is known as flange breakage or failure of the bar. After the bar has been in use for a short time, due to the severe strains and stresses to which it is subjected, a crack develops at the inner corner of the inner one of the spike slots and gradually extends to the adjacent center or inner one of the bolt openings from which it extends to the center of the bar, resulting in breaking of the bar in two. To overcome this difficulty, in some of the bars of older types, the flange portion has been materially thickened, and in others the flange has been widened to provide closed slots or openings for the spikes. In still others fillets have been provided at the slot corners. The filleting of the slot corners has not proved successful and the widening of the base flange to provide closed spike slots has also failed to insure against breakage. By making the base flange unusually thick and heavy, it is possible to avoid, to a great extent, this flange failure or breakage, but this is objectionable as very materially increasing the weight and the cost of the bar. The widening of the base flange to provide closed spike slots is also objectionable for the same reason.

The older types of bars above referred to are being discarded in favor of what is known as the balanced I-beam or 100% splice bar. This bar is so constructed that the area of the metal above the neutral zone, which is the plane of the axes of the securing bolts, is approximately equal to the area of the metal below such zone. Constructing the bar in this manner provides an equal distribution of the metal above and below the neutral zone so as to balance the resistance of the upper and lower portions of the bar to the strains and stresses to which it is subjected, insuring maximum efficiency. This type of bar is generally recognized by railroad engineers as closely approaching the ideal splice bar and possessing very high efficiency, and has come into extensive use. This bar, however, one objection. In order to properly balance the bar at opposite sides of the neutral zone, as above stated, the base flange of the bar is necessarily relatively thin and it is not practical to materially increase the thickness of this flange, as to do so would destroy, to a great extent, the high efficiency of the bar. This renders it impossible, from a practical standpoint, to thicken the base flange sufficiently to prevent flange failure or breakage of the bar, as was formerly done in the older types of splice bar. I have found that this objection can be overcome by properly disposing the spike slots in the flange of the bar. My invention, therefore, relates primarily to the disposition of the spike slots in the base flange of a splice bar having a comparatively thin base flange, in such manner as to prevent breakage of the bar due to the provision of the slot. More particularly, my invention is intended for use with what is known as the balanced I-beam or 100% type of splice bar.

Further objects and advantages will appear from the detailed description.

In the drawings:—

Fig. 1 is a transverse sectional view through a splice bar of the balanced I-beam type;

Fig. 2 is an outer face view of the bar provided with spike slots arranged in accordance with the present practice;

Fig. 3 is a view similar to Fig. 2 showing the bar provided with spike slots arranged in accordance with my invention.

The bar 1 is provided with a base flange 2 of a width to project beyond the base flange of the rail, as shown in Fig. 1. This flange is provided in its under face with a recess 3 providing what is called an "easement" in order that the bearing surface of the bar on the rail flange shall be approximately equal to the bearing surface of the head of the bar on the rail head. This bar is provided, through the web portion 4 thereof, with two central bolt receiving openings 5 and two end bolt openings 6 which are related in the usual manner well known in this

art. The bar is further provided with two spike receiving slots 7 and 7^a which are arranged in accordance with the present practice. By referring to Fig. 2 it will be noted that slot 7 is disposed within the space between the left hand opening 6 and the adjacent center opening 5; that is, the inner bolt slot is disposed within the space between the adjacent end bolt opening and the adjacent center bolt opening. The other spike slot 7^a is disposed well beyond the other bolt opening 6 and closely adjacent the right hand end of the bar. It is the practice to dispose the spike slots in this manner in order that the spikes at opposite sides of the joint may be disposed in staggered relation thus avoiding possible splitting of the tie, such as might result if the spikes were in alignment. I have found that the disposition of the spike slot 7 within the space between the bolt openings 6 and 5, as illustrated, and in accordance with the common practice, is responsible for what is commonly known as flange failures or breakage of the bar.

This fact has not been recognized by the railroad engineers and, due to the large percentage of flange failures or breakage in bars of this type, some engineers have discontinued providing the bars with spike openings, preferring to sacrifice the advantages of anchoring the rails to the ties in order that bars of this type can be used.

When a rail joint is new the area of strain lies between the two center bolt holes which are, ordinarily, spaced about six inches apart, though this spacing can be varied. As the bearing surfaces of the rails and the bars wear, the area of strain extends toward the ends of the bars to include that portion of the bar in which the inner spike slot 7 is located. In practice the area of strain does not extend toward the ends of the bar beyond the two bolt holes next to the center holes; that is, in the bar illustrated, beyond the bolt holes 6. As the inner slot 7 is disposed within the strain area and, in view of the fact that this slot weakens the flange 2, a crack, indicated at c, develops at the inner corner of slot 7 after the bar has been in use for a short time. With continued use of the bar this crack extends to the adjacent bolt hole 5, since the greatest strain is at the center of the bar, and the stresses to which the bar is subjected extend from the center of the bar at the top thereof diagonally downwardly and outwardly to the inner corner of the bolt slot 7. This crack c greatly weakens the bar and it quickly fractures along the line c', extending from the bolt hole 5 to the center of the bar at the top thereof, this completing the breaking of

the bar. A further fault resulting from arranging the spike slots in the manner illustrated, in accordance with present practice, is that the slot 7^a is disposed so closely adjacent the end of the bar that the portion of the flange beyond this slot frequently breaks off along the line c'' due to strains to which it is subjected by creeping of the bar, or because of expansion and contraction of the rails.

I have found that the objections above noted can be overcome by disposing the spike slots beyond the strain area of the bar, that is, beyond the spaces between the end bolt holes 6 and the center bolt holes 5, the spike slots being disposed between said spaces and the ends of the bar. In Fig. 3 the spike slot 7' is disposed beyond the horizontal center of the adjacent bolt hole 6 toward the adjacent end of the bar, and the slot 7^a is disposed inwardly toward the adjacent bolt hole 6 relative to the corresponding slot 7^a in Fig. 2, but is located between the adjacent end of the bar and the bolt hole. In my bar both of the slots 7' and 7^a are disposed beyond the strain area of the bar. The strain area is limited by the bolts extending through the end bolt holes 6 and does not extend beyond the end bolts, even when the joint is badly worn. By disposing the spike slots in the manner illustrated, beyond the strain area, the bar is not weakened within the strain area and, as a result, flange failures are eliminated. It will also be noted that the slot 7^a is disposed sufficiently remote from the adjacent end of the bar to eliminate the less serious breakage along the line c''. Bars with the spike slots arranged in accordance with my invention effectually eliminate all danger of breakage due to the provision of the spike slots, rendering it possible to employ the balanced I-beam or 100% type of bar with the additional advantage that this bar can be spiked to the ties for anchoring the rail ends.

What I claim is:—

1. A splice bar of the I-beam type including a base flange having spike openings disposed beyond the strain area of the bar.

2. A splice bar of the balanced I-beam type provided with a base flange having spike openings disposed between the ends of the bar and the respective end bolt holes.

3. A splice bar of the balanced I-beam type provided with a base flange having spike slots extending from its outer edge and disposed between the ends of the bar and the respective end bolt holes.

In witness whereof, I hereunto subscribe my name this 4th day of April, 1927.

GEORGE LANGFORD.
